UNITED STATES PATENT OFFICE

AUGUST L. WEFEL, OF KANSAS CITY, KANSAS

PNEUMATIC ACTION FOR MUSICAL INSTRUMENTS

Application filed August 15, 1927. Serial No. 212,926.

This invention relates to pneumatic action for musical instruments, and especially to what is known as the single valve type. While this device is shown as used on an automatic 5 musical instrument in which are employed pneumatic devices under the control of the perforated music sheets, yet it may be employed in other than musical instruments, which employ devices operated by pneumatic- 10 ics.

One of the objects of this invention is the provision of a housing for the striker pneumatic to which said pneumatic is attached, and which is demountably attached to the 15 action chest, and serves to separate adjacent pneumatics thus preventing undue interference with the action of the same. This housing also serves to hold the parts of the pneumatic in working alignment, and also permits 20 the removal of any single pneumatic without interfering with any of the other parts. It is of particular importance that the pneumatics are so positioned on the action chest 25 that the housing, which has but one side member, serves to house the adjacent sides of successive pneumatics. This arrangement of the housing and pneumatics permits all of the usual 88 pneumatics to be mounted on one action chest, and in one continuous row. 30 Another object is the provision of a pneumatic action having a removable side plate provided with a series of equally spaced valve 35 chambers, each of which has a valve seat held in position by having a press fit in said plate.

A further object of this invention is the contemplation of a pneumatic action having bearing plates located within the suction 40 chamber between the valves and pouches, which serve as the sole support for the entire series of slidably mounted valve stems. This construction permits the removal of any 45 stem from either side of the action chest without interfering with the position of the bearing plates, thus maintaining a good alignment of the valve stems at all times.

A still further object of this invention is the provision of a pouch having a press fit 50 in the front plate of the action chest, and

also having a diaphragm which is entirely mounted within the pouch casing.

Other objects are to produce a simple and inexpensive device, to reduce leakage to a minimum, and to obtain quickness and efficient action.

Minor objects of this invention will appear during the course of the detailed specification, referring to the accompanying drawings, wherein

Figure 1, is a cross sectional elevation of a pneumatic valve action, embodying this invention.

Fig. 2, is a rear elevation of the same, with some of the parts partially broken away.

Fig. 3, is a longitudinal plan section taken on line III—III of Fig. 2.

Fig. 4, is a perspective view of one of the striker pneumatics with the housing attached, and disengaged from the action chest.

Fig. 5, is a view similar to the one shown in Fig. 1, but with the pneumatic shown in the collapsed position.

Fig. 6, is an enlarged sectional view of the pouch, and

Fig. 7, is a sectional view taken on line VII—VII of Fig. 2.

Similar reference characters refer to like parts throughout the several views, and the numeral 8 designates a longitudinally disposed action chest having a suction chamber 9 from which the air is exhausted in the usual manner through the pipe 10. Action chamber 8 is provided with a front plate 11 which is securely attached to the main body of the chest by screws 12 and 13. The action chest is also provided with a rear plate 14, which is secured to the main body of the action chest by means of screws 15 and 16. Positioned within rear plate 14 is a series of 90 equally spaced valve chambers 17 which communicate with the suction chamber 9 thru ports 18. A bushing 19 having an atmosphere port 19' having an annular flange tightly fitted into valve chamber 17 until the flange of said port contacts with the outer wall of the rear plate. Thus, securing a tight joint to prevent the passage of air therethru, and permitting removal.

Front plate 11 is provided with a series of 100

equally spaced circular openings 20 in axial alignment with valve chamber 17, in which are press fitted flanged pouches 21, said flanges rest against the outer wall of the front 5 plate, thus permitting the removal of any pouch for repair. The pouches 21 are provided with sleeves 22 which communicate with the inner chambers 23 of said pouches, and are adapted to be engaged by tubes 24, 10 which are connected to the tracker bar 25 in the usual manner, and the perforated music sheet 25' passing over said tracker bar controls the flow of air into the pouch. Positioned in the valve chamber 17 between atmosphere ports 19 and port 18, is a valve 26 15 mounted on valve stem 27, which is adapted to alternately close said ports. One end of said valve stem is in operative relation with pouch 21, and is provided with a button 28 20 removably attached thereto. Valve stem 27 is slidably mounted in two longitudinally disposed bearing plates 29, which are preferably made from some non-corrosive material, such as celluloid, and are provided with openings 29' which permit the free flow of fluid 25 to all parts of the suction chamber. Bearing plates 29 extend the full length of suction chambers, and serve to carry all of the series of valve stems.

30 Carried by the action chest 8 thru the intermediacy of housings 30, which are securely attached to the action chest by means of screws 13 and 16, is a series of striker pneumatics 31, securely attached to housing 30 by means of screws 32. Each pneumatic is in communication with its corresponding valve chamber thru port 33 in which is pressed a thimble 34, which also engages the upper wall of said pneumatic. The movable part of the 35 pneumatic is provided with a longitudinal extension 35 having an adjustable contact member 36, which is adapted to operate the key action 37, in the usual manner.

Referring now to the pouch 21 more in detail, which is clearly shown in the enlarged Fig. 6. It will be noted that the diaphragm 38 is positioned wholly within the casing of the pouch 21, and is securely held in position by means of an internal sleeve 39, which securely binds said diaphragm against the inner wall of casing 21. Also the diaphragm 38 is provided with a wear plate 40, which serves to contact with the button 28. It will also be noted that the pouch is provided with a bleed 45 41, which is of proper proportion to permit the pouch to function properly. When the air is admitted thru the perforated music sheet 25', the air passes thru the opening in the tracker bar 25, thru the tube 24, then into the pouch chamber 23, forcing the diaphragm 38 against button 28 on valve stem 27, thus unseating the valve 26, which normally closes port 18, due to the atmospheric pressure exerted against it. When the valve moves to 60 close atmosphere port 19, the air which is in

the pneumatic 31 will be drawn into the suction chamber, and the pneumatic will be in the striking position, as shown in Fig. 5. When the air passes into the chamber 23 of the pouch 21, as just described, the bleed 41 70 will permit only a small portion of said air to enter the suction chamber, but is sufficiently large to allow the diaphragm 28 to pass back to its normal position as shown in Fig. 1, when the air is again cut off by the music sheet 25'.

Referring now to Fig. 4, showing more in detail the housing 30, to which the pneumatic 31 is attached by means of screws 32, which are preferably counter sunk and flush with housing. Housing 30 is provided with upturned ears 42 and 43, adapted to engage rear plate 14, and front plate 11, respectively. Screw 16 serves to securely clamp ear 42 against the rear plate, and also to secure said rear plate to the main body of the action chest. Likewise, the screw 13 secures ear 43 to the front plate 11, and also secures said front plate to the main body of the action chest. Extending downwardly and in juxtaposition with one of the side walls of the pneumatic 31, is the side wall 44 of housing 30. Said side wall extends to the lower edge of the pneumatic, and is co-extensive therewith. It is apparent that should one of these pneumatics become defective, it could easily be removed by removing screws 16 and 13, then pulling the housing free from the action chest. This could be done without interfering with adjacent pneumatics. Repairs 95 could then be made, or the pneumatic could be removed from the housing by removing screws 32, and replacement made. Since the housing 30 has but one depending side wall, which serves as a housing and guide for adjacent walls, the pneumatic is more accessible when removed and attached to the housing, as shown in Fig. 4.

I do not limit this invention to the structure shown and described, as many modifications within the scope of the appended claims may be made without departing from the spirit thereof.

Having thus described this invention, what is claimed as new, and desired to be secured by Letters Patent is:

1. In a pneumatic action for musical instruments, an action chest having a detachable side and an exhaust chamber, a valve chamber positioned within said detachable side having an atmosphere port and a port opening into said exhaust chamber said ports being formed in said detachable side, a valve disposed between the said ports, a pneumatic means carried by said action chest adapted to operate said valve, and a striker pneumatic carried by said action chest adjacent said valve chamber and communicating therewith.

2. In a pneumatic action for musical instruments, an action chest having a detach-

- able side and an exhaust chamber, a series of aligned and spaced apart valve chambers positioned within said detachable side, each valve chamber having an atmosphere port and a port opening into said exhaust chamber and a valve in each valve chamber disposed between said ports said ports being formed in said detachable side, a series of pneumatic means carried by said action chest, each of said pneumatic means being adapted to operate one of said valves, and a series of striker pneumatics carried by said action chest, one of which is adjacent each of said valve chambers and communicates therewith.
- 5 3. In a pneumatic action for musical instruments, an action chest having opposite detachable sides and an exhaust chamber, a series of spaced apart valve chambers positioned within one of said detachable sides, each valve chamber having an atmosphere port and a port opening into said exhaust chamber, a valve in each valve chamber positioned between said ports and having a valve stem slidably mounted in bearing plates positioned entirely within said exhaust chamber and common to all valve stems, a series of pneumatic means carried by said action chest, each of said pneumatic means being adapted to operate one of said valves, and a series of striker pneumatics carried by said action chest, one of which is adjacent each of said valve chambers and communicates therewith.
- 10 4. In a pneumatic action for musical instruments, an action chest having a detachable side and an exhaust chamber, a series of spaced apart valve chambers positioned within said detachable side, each valve chamber having an atmosphere port and a port opening into said exhaust chamber, a valve in each valve chamber adapted to close either of said ports, a series of pneumatic pouches press fitted into openings in the side wall of said action chest, each of said pneumatic pouches being in communication with a suitable tracker bar aperture and in operable connection with one of said valves, and a series of striker pneumatics carried by said action chest, each of said striker pneumatics being adjacent one of said valve chambers and communicating therewith.
- 15 5. In a pneumatic action for musical instruments, an action chest having a detachable side and an exhaust chamber, a series of spaced apart valve chambers positioned within said detachable side, each valve chamber having an atmosphere port and a port opening into said exhaust chamber, a valve in each valve chamber adapted to close either of said ports, a series of pneumatic pouches carried by the wall of said action chest, each of said pneumatic pouches being in communication with a suitable tracker bar aperture and in operable connection with one of said valves, an operating diaphragm entirely contained within each of said pneumatic pouches, and a series of striker pneumatics carried by said action chest, each of said striker pneumatics being adjacent one of said valve chambers and communicating therewith.
- 20 6. In a pneumatic action for musical instruments, an action chest having a detachable side and an exhaust chamber, a series of spaced apart valve chambers positioned within said detachable side, each valve chamber having an atmosphere port and a port opening into said exhaust chamber, a valve in each valve chamber disposed between said ports, a series of pneumatic means carried by said action chest, each of said pneumatic means being adapted to operate one of said valves, a series of independent housings removably attached to said action chest, each housing of said series being adjacent one of said valve chambers, and a striker pneumatic carried by each of said housings and in communication with said adjacent valve chamber.
- 25 7. In a pneumatic action for musical instruments, the combination, with an action chest having an exhaust chamber, a valve chamber having an atmosphere port and a port communicating with said exhaust chamber, a valve positioned between said ports and pneumatic means in operable connection with a tracker bar aperture for operating said valve, of a housing positioned adjacent said valve chamber and removably attached to said action chest, and a striker pneumatic carried by said housing and in communication with said adjacent valve chamber.
- 30 8. In a pneumatic action for musical instruments, the combination, with an action chest having a detachable side and an exhaust chamber, a series of spaced apart valve chambers positioned within said detachable side, each valve chamber having an atmosphere port and a port opening into said exhaust chamber, a valve in each valve chamber disposed between said ports, a series of pneumatic means carried by said action chest, each of which is adapted to operate one of said valves, of a series of housings removably attached to said action chest, each of said housings being adjacent one of said valve chambers and having a striker pneumatic carried thereby, an air passage connecting said pneumatic and adjacent valve chamber, and a side wall of each housing positioned between adjacent sides of successive striker pneumatics and co-extensive therewith.
